JOSEPH PRICE, OF NEW YORK, N. Y., ASSIGNOR TO THE GRISCOM-RUSSELL COMPANY, OF NEW YORK, N. Y., A CORPORATION OF DELAWARE.

HEAT EXCHANGER.

Application filed September 29, 1925. Serial No. 59,260.

This invention relates to heat exchangers adapted particularly for cooling and liquefying the vapors resulting from the distillation of petroleum and more generally for cooling gases and liquids of any kind.

In localities such, for example, as the oil fields of Oklahoma, where the water available for cooling purposes contains relatively large amounts of various salts which crystallize out of the water and form scaly deposits, a great deal of difficulty has been experienced in operating heat exchangers. In this region the conventional type of tube and shell heat exchanger is unsuitable because of the carbonate and sulfate scales in the cooling water. Some refining plants have even resorted to the treating of the circulating water to remove the objectionable salts, such as is many times done economically in the preparation of boiler feed water. However, the tremendous volume of circulating water required in a refining plant renders this treatment extremely expensive and undesirable.

The object of the present invention is to provide an improved surface type heat exchanger which is substantially self-scaling, and is commercially practicable because of its simple construction and low cost of manufacture.

According to this invention, the heat exchanger consists of assembled units, each comprising a pair of headers which are held by suitable spacers. Tubes, preferably arranged in a relatively shallow layer of two or more rows, are connected to each pair of headers. The medium to be cooled flows through the headers and tubes. The spacers should be made of a metal having a lower coefficient of expansion than the metal of the tubes. Steel may be used for the spacers and a non-ferrous metal such as admiralty metal or brass for the tubes. The spacers prevent the separation of the headers when the tubes are elongated by expansion due to the passage of a hot medium therethrough. The tubes are bowed slightly so that a relatively small elongation of the tubes by expansion produces a relatively large deformation and thereby exerts a loosening effect upon the scale deposited on the outside of the tubes.

The units are assembled into a heat exchanger, preferably, by stacking in an appropriate rack which can conveniently be

made of relatively light structural steel. The cooling water containing the salts, which deposit on the outside of the tubes and form the scale, is sprayed over the surface of the tubes of the several units. The water can be collected for recirculation when desirable. The rack is preferably so constructed as to leave the tier of horizontal units exposed to the atmosphere, thus securing an added cooling effect, but the tier may be enclosed if found desirable.

The invention is illustrated by way of example in the accompanying drawings in which—

Figure 1 is a view partially in side elevation, partially in section, of a heat exchanger constructed in accordance with the present invention;

Figure 2 is an end view of the heat exchanger;

Figure 3 is an enlarged horizontal section through one of the heat exchanger units taken on the line 3—3 of Figure 4;

Figure 4 is an enlarged longitudinal section taken through the heat transferring elements of a heat exchanger including a smaller number of units than that shown in Figure 1;

Figure 5 is an enlarged fragmentary section, taken transversely of the heat exchanger and longitudinally through the headers, showing also a modified form of spraying device;

Figure 6 is a transverse section on line 6—6 of Figure 3;

Figure 7 is a transverse vertical section through a modified form of heat exchanger.

Referring now to these drawings, and first to Figure 3, the unit of which the heat exchanger is made comprises the headers 10 and 11, between which extend the tubes 12. The headers are of shallow elongated box-like construction as shown in Figure 4 and are adapted to receive only a relatively few rows of tubes 12. Two horizontal parallel rows of tubes are preferable. These tubes are secured in apertures 13 in each of the headers in any appropriate manner, such for example as by expanding the ends of the tubes with a suitable tool, or by welding. It is better to secure the tubes by the expansion method than by welding inasmuch as individual tubes can then be readily replaced if desired. Opposite the apertures 13 are corresponding apertures 14 through

the outside walls of the headers which are normally fitted with threaded plugs, readily removable, however, when it becomes necessary after long and continuous operation of the heat exchanger to clean the interiors of the condenser tubes 12.

The tubes 12 instead of being straight are slightly bowed out of a straight line so that, when the headers 10 and 11 are held in fixed position and the tubes are subjected to elongation by heat expansion, a relatively large deformation of the tubes will occur. Similarly, the subjection of the tubes to cooling causes them to shorten and straighten out. Either such elongation or shortening of the tubes produces a distortion of the tube surface that cracks or loosens any scale which may have formed on the outside surfaces of the tubes. In the drawings the bowing of the tubes has been somewhat exaggerated for the sake of clearness but the amount of bowing used in practice is relatively slight. The smaller the degree of bow within such limits as necessary to protect the tubes from rupture, the greater is the surface distortion for the same amount of elongation or shortening.

In order to maintain the position of headers 10 and 11 fixed with respect to one another while the tubes 12 are being subjected to distortion, the spacers 15 and 16 extend longitudinally of the condenser element one on each side of the tubes 12 and are firmly secured at their ends to the headers 10 and 11. These spacers are made of steel angle bars having a face somewhat wider than the layer of tubes as may be seen in Figure 4 so as to form a certain degree of protection for the tubes against mechanical injury. The spacers are secured to the headers 10 and 11 by bolts 17, by welding or by any appropriate means.

Intermediate the headers 10 and 11, three transverse bars 18 pass above, between and below the two rows of tubes 12 and are welded at their opposite ends 19 to the spacers 15 and 16 (see Figures 4 and 6). These bars pass in close proximity to the surfaces of tubes 12 but are not fastened to the tubes. They are relatively rigid and, when the tubes are subjected to elongation, compel the bowing thereof to take place in a single horizontal plane, the tubes moving slightly laterally with respect to bars 18 and coming in contact therewith if there is any tendency of the tubes to twist or warp or move in any other than the horizontal direction.

The headers 10 and 11 are provided with projecting portions 20 and 21 respectively and these projections are provided with flanged or other suitable couplings 22 by which connections for conveying the vapor or other fluid to and from the units are made. These projections may be placed at any con-

venient point longitudinally of the headers but they are preferably located at the center. Headers 10 and 11 are absolutely identical when projections 20 and 21 are centrally placed. Hence the same header can be used at both ends of the heat exchanger unit and the unit will be assembled with the projections 20 and 21 extending either in the same or opposite directions depending upon convenience.

Referring now to Figures 1 and 2 of the accompanying drawings there is here shown a complete heat exchanger constructed of the units described. In this heat exchanger a rack comprising upright posts 23 of steel connected by longitudinally extending angle bars 24 and by cross members 25 supports the several units one above the other with their respective layers of tubes 12 in horizontal position. The horizontal flanges of the angle frame members 15 and 16 form convenient means for supporting the units upon the horizontal bars 24.

The connecting projection 20 of the uppermost unit is turned upward and connecting projection 21 downward, those of the next lower unit in the opposite directions, and so on down through the heat exchanger, so that the units are connected in series with one another from top to bottom. It will be noted that even with this reversal of the connecting projections, the units are identical with one another and in order to connect them as shown in Figure 1, it is only necessary to arrange adjacent units upside down with respect to one another. Inasmuch as there are no right and left connections and inasmuch as these units are identical one with another, it is only necessary to add on or take off units when it is desired to change the capacity of the heat exchanger. Moreover, great convenience in manufacturing results because it is only necessary to manufacture one type of unit.

The vapor or other fluid to be cooled is fed to the heat exchanger through the pipe 26 in which is a controlling valve 27. The cooling water under the control of valve 28 in a pipe 29 flows into a distributing pan 30 which is shown in section in Figures 1 and 2 in order to bring out the plurality of apertures 31 extending throughout the area of the bottom of this pan. The distributing tray 30 is supported upon one set of the longitudinal bars 24 above the uppermost unit. By means of apertures 31 the water is sprayed upon the outside surface of the tubes 12, striking first the tubes of the uppermost unit and thence dropping downwardly into contact with the subsequent layers of tubes. The water dripping over the surfaces of the tubes is collected at the bottom of the tier by means of a pan 32, which also is conveniently supported upon one set of the bars 24, and flows out through

pipe 33, either to waste or to be recirculated over the pipes after appropriate cooling.

As the vapor or other fluid passes downwardly through the series of units it is cooled, and flows out of pipe 34 which is connected to the flanged coupling 22 of the bottom element. When condensing oil vapor, it may be desirable to draw off "separate cuts" at different temperatures and for this purpose one or more intermediate outlet pipes 35 may be connected to one or more of the headers 10 or 11 or any of the units desired. In order to make this connection it is only necessary to drill a hole 36 (see Figure 4) in one of the flat sides of one of the headers 10 or 11, and around this opening, drill and tap suitable holes for tap bolts 37 for the purpose of securing in place a flanged connection 38. Any of the headers 10 and 11 can be drilled in this manner so that it is not necessary to provide a specially constructed header where it is desired to withdraw condensate at an intermediate temperature.

In the heat exchanger shown in Figures 1 and 2, the stack being of an open frame work construction and merely serving to support the several units, the atmosphere is free to circulate around and between the tubes and facilitate the cooling of the vapor or other fluid. If desired, however plates 39 may be secured to the rack along each side so as to prevent the spattering of the cooling water as it flows down over the tubes. These plates may be seen in Figure 5. Also, instead of the distributing tray 30 a plurality of longitudinally arranged pipes 40, as shown in the same figure, may be used. These pipes are provided along their lower surfaces with apertures 41 by which the cooling water is sprayed upon the tubes.

As an additional modification of the construction the rack containing the units as shown in Figure 1 may be placed in a tank 42 as shown in Figure 7 in which case the tank will contain cooling water and the tubes will be submerged therein. Appropriate means can be provided to produce a continuous circulation of the cooling water in tank 42.

Referring again to Figure 1 a steam supply pipe 43 provided with a valve 44 is connected to the inlet pipe 26 for the vapor at a point between control valve 27 and the heat exchanger. This is for the purpose of removing the scale which collects in large quantities upon the surfaces of the condenser tubes 12. Steam at a relatively high temperature, say for example steam at 100 pounds gauge pressure is admitted through valve 44 after closing the valve 27 to shut off the vapor supply and valve 28 to shut off the cooling water supply. This sudden admission of steam at a temperature considerably above the normal working tem-

perature of tubes 12 causes them to expand and elongate. Owing to the different metals employed in the tubes and spacers, the former will expand very much faster than the latter. The resulting bowing of the tubes loosens the scale so that it will drop off, particularly under the action of the cooling water when the heating surface becomes active again, or upon the stream of steam by a stream of cold water.

The application of steam through pipe 43 is made periodically whenever an incrustation of scale has built up on the surfaces of the tubes to such an extent as to appreciably reduce the efficiency of the heat exchanger. The steaming operation, however, requires only from 1 to 3 minutes' time and therefore affects the operation of the apparatus to so small an extent that it can be repeated at extremely frequent intervals without difficulty.

It will be noted that the force tending to separate headers 10 and 11 of each condenser element is resisted entirely by the spacers 15 and 16 of each particular unit. That is, the stress which occurs in the spacers of any one element is entirely independent of the stress that may occur in any of the other units. Hence, if some of the units, for example, the upper units, are subjected to a higher temperature than the lower units, no appreciable stress results in the heat exchanger as a whole. This is an important feature inasmuch as it provides a structure which is rugged and which is not liable to damage during the de-scaling operation at the hands of an unskilled operator.

By constructing a heat exchanger in accordance with this invention a self-scaling condenser is provided at such low cost of manufacture that it can be economically used in the numerous petroleum refining plants and in many other installations where bad circulating water conditions would materially increase the maintenance cost of conventional tube and shell heat exchangers.

In addition, the invention has an extremely important manufacturing advantage. It provides a standard heat exchanger unit which can be manufactured in large quantities for stock and used for a variety of duties by merely changing the number of units which are assembled in series or parallel.

I claim:

1. A heat exchanger for use with cooling water from which scale-forming substances deposit comprising a plurality of units, each unit including a pair of headers connected by tubes, said tubes being slightly bowed out of a straight line whereby a relatively small elongation of the tubes through heat expansion produces a relatively large deformation of the tubes and thereby exerts a loosening action on the deposited scale, said headers

- of each element being independently held in spaced relation by means for preventing the separation of the headers when the tubes are subjected to a greater amount of elongation than said spacing means. 5
2. A heat exchanger comprising a plurality of units spaced vertically one above the other, each of said units including a pair of headers connected by a plurality of horizontally bowed tubes and spacers to hold the headers of each unit from spreading, means for spraying water over the surface of the uppermost unit, and means for collecting the water from below the bottom unit. 10
- 15 3. A heat exchanger, comprising a vertical frame-work having a plurality of pairs of longitudinal bars supported in vertically spaced relation by a pair of verticals at each end thereof, each pair of said longitudinals supporting thereon a separate heat transferring unit slidably mounted at each end thereof, each unit including a pair of headers connected by tubes, said tubes being slightly bowed out of a straight line, whereby 20 a relatively small elongation of the tubes through heat expansion produces a relatively large deformation of the tubes and thereby exerts a loosening action on the deposited scale, said headers of each unit being independently held in spaced relation by means for preventing the separation of the headers when the tubes are subjected to a greater amount of elongation than said spacing means. 25
- 30 4. In a heat exchanger, the combination of an atmospheric sprinkler system comprising a box frame, an overhead source of water supported thereon, a sprinkler tray supported vertically beneath said source and a collector-sump vertically beneath said sprinkler tray and a closed condensing conductor comprising a series of separate parallel horizontally bowed heat-transferring units supported vertically in the box frame and connected in vertical S-form, and having an inlet and an outlet. 35
- 40 5. In a heat exchanger of the class described, a heat-transferring element having an inlet header slidably supported in a horizontal plane in a vertical framework and an outlet header slidably supported in the framework in the same horizontal plane, a spacer bar connecting said headers and a plurality of sets of heat-transferring tubes extending in parallel horizontal planes there- 50 between, each set of tubes comprising a plurality of tubes having a higher coefficient of expansion than said spacer bar and having a permanent bowl-shape in parallel horizontal planes, each set being rigidly maintained in a horizontal plane and separated from the adjacent set by a rigid transversely extending bar attached by its ends to the framework near the middle of the length of the tubes, said outlet header having at its bottom side a downwardly projecting conduit supported by and fluidly connected to a similar and upwardly projecting conduit on the upper face of the inlet header of the next succeeding heat- 55 transferring element. 60
- 55 6. A heat exchanger, comprising a vertical frame work, having a plurality of pairs of longitudinal bars supported in vertically spaced relation in parallel planes by a pair of verticals at each end thereof, the top-most pair of said longitudinals supporting a water sprinkler and each succeeding pair of said longitudinals supporting a separate heat-transferring element slidably mounted 60 at each end thereon, each of said heat-transferring elements having a conduit projecting in opposite vertical directions from each end thereof, said conduits having means whereby the successive elements may be connected in series flow relation at alternate ends from the top-most element downwardly through the vertical frame work, said top-most element having a two-way inlet connection to a source of fluid to be treated 65 and to a source of steam respectively, and the bottom-most element having a discharge connection, and the bottom-most pair of longitudinals supporting a cooling water collecting sump. 70
- 75 7. In testimony whereof I affix my signature. 80
- 85 JOSEPH PRICE. 90
- 95

of each element being independently held in spaced relation by means for preventing the separation of the headers when the tubes are subjected to a greater amount of elongation than said spacing means.

2. A heat exchanger comprising a plurality of units spaced vertically one above the other, each of said units including a pair of headers connected by a plurality of horizontally bowed tubes and spacers to hold the headers of each unit from spreading, means for spraying water over the surface of the uppermost unit, and means for collecting the water from below the bottom unit.

15 3. A heat exchanger, comprising a vertical frame-work having a plurality of pairs of longitudinal bars supported in vertically spaced relation by a pair of verticals at each end thereof, each pair of said longitudinal

20 supports thereon a separate heat transferring unit slidably mounted at each end thereof, each unit including a pair of headers connected by tubes, said tubes being slightly bowed out of a straight line, where-

25 by a relatively small elongation of the tubes through heat expansion produces a relatively large deformation of the tubes and thereby exerts a loosening action on the deposited scale, said headers of each unit being inde-

30 pendently held in spaced relation by means for preventing the separation of the headers when the tubes are subjected to a greater amount of elongation than said spacing means.

35 4. In a heat exchanger, the combination of an atmospheric sprinkler system comprising a box frame, an overhead source of water supported thereon, a sprinkler tray supported vertically beneath said source and a

40 collector-sump vertically beneath said sprinkler tray and a closed condensing conductor comprising a series of separate parallel horizontally bowed heat-transferring units supported vertically in the box frame and connected in vertical S-form, and having an inlet and an outlet.

45 5. In a heat exchanger of the class described, a heat-transferring element having an inlet header slidably supported in a hori-

zontal plane in a vertical framework and 50 an outlet header slidably supported in the framework in the same horizontal plane, a spacer bar connecting said headers and a plurality of sets of heat-transferring tubes extending in parallel horizontal planes there- 55 between, each set of tubes comprising a plurality of tubes having a higher coefficient of expansion than said spacer bar and having a permanent bowl-shape in parallel horizontal planes, each set being rigidly 60 maintained in a horizontal plane and separated from the adjacent set by a rigid transversely extending bar attached by its ends to the framework near the middle of the 65 length of the tubes, said outlet header having at its bottom side a downwardly projecting conduit supported by and fluidly connected to a similar and upwardly projecting conduit on the upper face of the inlet header of the next succeeding heat- 70 transferring element.

6. A heat exchanger, comprising a vertical frame work, having a plurality of pairs of longitudinal bars supported in vertically spaced relation in parallel planes by a pair of verticals at each end thereof, the top-most pair of said longitudinals supporting a water sprinkler and each succeeding pair of said longitudinals supporting a separate heat-transferring element slidably mounted 80 at each end thereon, each of said heat-transferring elements having a conduit projecting in opposite vertical directions from each end thereof, said conduits having means whereby the successive elements may be connected in series flow relation at alternate ends from the top-most element downwardly through the vertical frame work, said top-most element having a two-way inlet connection to a source of fluid to be treated 85 and to a source of steam respectively, and the bottom-most element having a discharge connection, and the bottom-most pair of longitudinals supporting a cooling water collecting sump. 90

95 In testimony whereof I affix my signature.
